HYDRAULIC POWER UNIT

Stewart B. McLeod, Dearborn, Mich., assignor to
 Detroit Harvester Company, Detroit, Mich., a
 corporation of Michigan

Application March 21, 1949, Serial No. 82,529

2 Claims. (Cl. 103—126)

1

The present invention relates to a hydraulic power unit and more particularly to a combined pump, motor, reservoir and control valves therefor.

The present invention is capable of general application but may be used in the type of system disclosed in my prior Patent 2,388,755, granted November 13, 1945.

This application is a continuation in part of my co-pending application, Serial No. 776,635, filed September 29, 1947, now Patent No. 2,588,644.

In accordance with the present invention, a hydraulic system including a reversible pump is provided with a by-pass and reservoir connection unit which serves to seal the pressure side of the pump and open the suction side of the pump to the reservoir to compensate for unequal volumes of flow due to piston rod displacement when the cylinders are used. In one embodiment of the present invention the mechanism is further constructed to afford pressure relief so as to prevent development of excessive pressures at the pressure side of the pump. Inasmuch as in the present construction the fluid flow is not through the unit to the cylinders or fluid motors, the unit can be made without regard to flow areas through the valve and consequently may be relatively small and inexpensive.

It is an object of the present invention to provide an improved hydraulic power unit characterized by its efficiency, extreme simplicity, the compactness of its arrangement and the economy with which it may be produced.

More specifically, it is an object of the present invention to combine a pump, motor, reservoir and control valves for supply fluid in a novel arrangement whereby a hydraulic system in which said unit is connected remains always fully charged with fluid.

It is a further object of the present invention to provide a reversible pump and reservoir unit in which the reservoir is connected at all times during operation of the pump to the suction side thereof.

It is a further object of the present invention to provide a by-pass connection for a reversible pump which remains open when the pump is idle to provide for manual operation of normally fluid operated mechanism but which is closed by operation of the pump in either direction.

It is a further object of the present invention to provide a by-pass between the pressure and suction sides of a pump adapted to remain open when the pump is idle, to close during normal

pump operation, and to reopen in the event of excessive pressure at the pressure side of the pump.

It is a feature of the present invention to provide a hydraulic power unit comprising a block having a recess therein for the reception of a rotary pump, a motor supported from the block in driving relation with the pump, passages for circulating fluid communicating at one side of the recess with opposite sides of the pump, a fluid supply reservoir carried by the block having passages communicating at the opposite side of the recess with opposite sides of said pump, and valves for controlling the flow of supply fluid between the reservoir and pump.

Other objects and features of the invention will become apparent as the description proceeds, especially when taken in conjunction with the accompanying drawings, wherein:

Figure 1 is an elevation, partly in section, of my improved unit;

Figure 2 is a section on the line 2—2 of Figure 1;

Figure 3 is a section on the line 3—3 of Figure 2;

Figure 4 is a perspective view of the valve engaging element employed in my improved construction;

Figure 5 is a section on the line 5—5 of Figure 1;

Figure 6 is a fragmentary section on the line 6—6, Figure 5;

Figure 7 is a vertical elevation, partly in section, of a somewhat different embodiment of the present invention;

Figure 8 is a section on the line 8—8 of Figure 7;

Figure 9 is an enlarged fragmentary section on the line 9—9 of Figure 8.

40 The present construction comprises a block 10 carried at the top of a motor housing 30 and supporting at its upper surface a fluid supply reservoir 40.

The block 10 is provided with a cylindrical recess 11 at its upper surface in which is mounted a rotary pump of known type. Preferably the pump is of the type comprising an annular, internally toothed rotor 12a having a gear 12b therein, the teeth of the gear being one less in number than the internal teeth of the rotor. Communicating with the bottom of the recess 11 are a pair of fluid circulating passages 13 and 14 which in turn communicate with tapped connecting portions 15 and 16, respectively. It will be appreciated that the device illustrated is for

use in supplying fluid to a hydraulic system and that the system will include conduits having threaded connectors cooperating with the connecting portions 15 and 16. Passages 13 and 14 serve as inlet and outlet connections to the pump, depending upon the direction of rotation thereof. In other words, the pump is reversible and in one instance fluid will be drawn in through the passage 13 and discharged through the passage 14, whereas when the pump is rotated in the opposite direction, the direction of flow of the fluid is reversed.

The block 10 is provided with an opening 17 therethrough which is coaxial with the cylindrical recess 11 and which receives the drive shaft 18 of an electric motor indicated at 19. The lower end of the opening 17 is enlarged to receive a suitable seal and bearing 20 for the shaft 18.

The motor 19 is carried within the housing 30 which is assembled to the block 10 by means of long attaching screws 32 threaded into tapped recesses in the block 10 as indicated at 33. A conductor for supplying power to the motor 19 is illustrated at 34.

Located on the upper surface of the block 10 is the reservoir 40. As illustrated, the reservoir 40 may be in the form of a sheet metal cup having a removable closure 41. The bottom 42 of the reservoir 40 is provided with a circular opening 43 surrounding the rotor 12a, and a sealing gasket 44 is provided between the bottom 42 and the upper surface of block 10.

Located within the reservoir 40 is a valve 50 which serves to provide and control fluid supply passages between the reservoir and the pump. A first passage 51 communicates with a short, relatively small transverse passage 53 formed in the central portion of a boss 54. At its outer ends the passage 53 communicates with enlarged end passages or openings 55 and 56. Intermediate the passage 53 and the two enlarged end openings 55 and 56 are conical valve seat portions 57 and 58, respectively. Located within the enlarged openings 55 and 56 are ball valves 59 and 60, respectively. The outer ends of the openings 55 and 56 are closed by threaded plugs 61 and 62, respectively, and intermediate the plugs 61 and 62 and the ball valves 59 and 60 are balancing springs 63 and 64, respectively. Extending laterally from the enlarged openings 55 and 56 are ports 65 and 66 which communicate with the side of the gear pump opposite to ports or passages 13 and 14.

Intermediate the ball valves 59 and 60 is a 55 slidable element 67, shown in detail in Figure 4. The element 67 may conveniently be formed of metal of triangular cross section and preferably has rounded corners, as indicated at 69. The element 67 is slidably received in the passage 53 but by virtue of its triangular cross section it permits flow of fluid through said passage 53.

The element 67 is of such length that when the ball valves 59 and 60 are symmetrically located with respect to their seats 57 and 58, respectively, both valves are in partially open position. On the other hand, it will be readily apparent that when one of the ball valves 59 or 60 closes by virtue of pressure existing in the passage with which it communicates, the other of the ball valves is mechanically moved to full open position.

Springs 63 and 64 are of substantially equal strength so that in the absence of pressure in

the device the ball valves stand in the position shown in Figure 1.

The assembly of the parts includes the use of assembly bolts 72 (Figure 2) which extend through the valve body 50 into suitably tapped openings formed in the upper surface of the block 10.

The cover or closure 41 for the reservoir 40 is illustrated as secured in place thereon by means of a tie bolt 70 threaded at its lower end into a suitably tapped recess 70a in the upper surface of the valve body 50 and provided at its upper end with a nut 71.

The under surface of the valve body 50 rests directly on the upper surface of the pump comprising the gear members 12a and 12b and thus constitutes the upper closure for the pump chamber, the lower portion of which is constituted by the cylindrical recess 11 formed in the upper surface of the block 10.

The valve body 50 is provided with a transverse passage 73 which communicates with an opening 74 provided in the gear member 12b and which permits flow of oil therethrough to relieve pressures which might otherwise build up. The gear 12b is provided with a keyway 75 which receives a driving ball or key 76 seated in a recess at the end of the drive shaft 18.

An oil slinger 78 is carried by the shaft 18 below the bearing structure 20 and any oil which passes downwardly of the shaft below the bearing encounters the oil slinger and is thrown thereby in radial direction. The attaching bolts 32 which connect the motor to the block 10 are provided with oil resistant rubber sleeves 79 which serve to seal passages through which the bolts 32 extend.

The mounting means for the assembly comprises a ring 110 to which is suitably secured a bracket 112 having ears 113 provided with openings 114 which receive rubber mounting bushings 115. In order to prevent rotation of the motor, pump, valve and reservoir assembly relative to the mounting ring 110, a recess 116 is provided on the upper surface of the motor housing and a portion of the ring 110 is lanced inwardly to form a finger 118 which seats in the recess 116 and thus serves as a positive means for preventing relative rotation between the ring 110 and the remainder of the assembly.

If desired, a similar finger may be provided at the upper edge of the ring 110 and may cooperate with a correspondingly formed recess provided at the under side of the block 10. This will serve the additional function of positively preventing even slight relative rotation between the motor (and hence the gear pump members 12a and 12b) and the block 10 and associated structure. Moreover, since the fastening elements 32 are adapted to draw the motor assembly toward the block 10, they will insure positive clamping of the ring between these elements and will contribute to the rigidity of the structure as well as the proper alignment of the motor shaft in the block 10.

In addition to serving as means for mounting the unit, the ring 110 serves as a closure member for the space between the top of the motor and the under side of the block 10. The top of the motor has a circular boss 120 recessed at diametrically opposite points 121 to receive screws 32 and sleeves 79. Outwardly from the boss 120 there is provided an annular seat 122 which receives the lower edge of the ring 110. A plurality of recesses 119 are provided in the lower edge of the ring and cooperate with the upper surface

of the motor assembly to provide passages which permit the escape of oil or hydraulic fluid which might otherwise accumulate within the space.

In order to prevent leakage of fluid from the reservoir 40, which might otherwise occur due to motion of the vehicle or inclination of the vehicle, the cover 41 is provided with an annular sealing ring of inverted U-shape cross section indicated at 115 in Figure 1. The cover 41 has a correspondingly shaped downwardly opening groove 116 cooperating with the sealing ring 115 and beneath the groove 116 the cover 41 has a downwardly and outwardly flaring flange 118. This construction provides a fluid tight seal at the juncture between the cover 41 and the reservoir 40.

In use the cover 41 is clamped downwardly against the top of the reservoir 40 by means of the nut 71 threaded to the upper end of the bolt 70. A seal is also provided where the bolt 70 passes through an opening 120 in the cover 41. This seal comprises a suitable resilient gasket 122 which may be formed of an oil resistant rubber or the like and which is received in a downwardly flaring cup 124. The gasket 122 is in its uncompressed condition somewhat larger than the cup 124. Accordingly, as the nut 71 is tightened down and the material of the gasket 122 is compressed, it is forced by the cup 124 to expand inwardly and thus to make a fluid tight seal with the upper surface of the cover 41 and with the upper portion of the bolt 70. By this construction the reservoir is rendered fluid tight and the possibility of fluid spilling or leaking therefrom in use is completely avoided. The sealed construction of the reservoir is rendered possible due to the fact that the entire system in which the power unit is included is a closed system.

The operation of my improved device is believed to be readily apparent, especially when taken in consideration with the full discussion of my prior construction contained in Patent 2,388,755 and my co-pending application Serial No. 776,635, now Patent No. 2,588,644, of which the present application is a continuation in part. However, for completeness, it may be noted that upon the establishment of pressure by operation of the pump in the circulating fluid passage 14, pressure will simultaneously be established within the enlarged opening 56 and will close the valve 60. At this time suction is established in the passage 13 at the opposite side of the block 10 and also in the opening 55. At this time, since the ball valve 60 is forced on its seat by pressure, the ball valve 59 is in fully open position, thus establishing communication between the interior of reservoir 40 and the suction side of the pump. As a result of this, and in the event that the demand for fluid in the pressure side of the circulating system is more than can be supplied from the suction side thereof, the difference in fluid required is made up by withdrawing fluid from the reservoir, as will be readily apparent.

Another valuable function of the balanced arrangement of ball valves is serving as a by-pass around the pump. Thus where the unit is employed as a power unit for raising and lowering a convertible top, or other use, the balanced valves provide for a limited by-pass flow of fluid around the pump, and permits manual operation of the operated device. In this case flow of fluid is in one direction or the other through the following sequence of passages:

passage 14, the pump, passages 66, 53, 55, the other side of pump, and passage 13. Slow manual operation is permitted, whereas rapid operation with corresponding rapid flow of fluid through the valved passages will close one or the other of the ball valves, depending on the direction of flow.

Referring now to Figures 7 to 9, there is shown a somewhat different embodiment of the invention which while it operates on the same principles as the embodiment previously described, has the additional function of pressure relief, as will presently appear. In this case the hydraulic power unit comprises a motor housing 80, a block 81 serving as the support for a pump 82 including pump gears 103 and 104, a reservoir 83 and a by-pass and reservoir connection unit indicated generally at 84. With the exception of the by-pass and reservoir connection unit 84, the construction of this embodiment may be identical with that illustrated in Figure 1 and will therefore not be described in detail.

However, the by-pass and reservoir connection unit 84 provides the additional function of affording pressure relief in the event of attainment of excessive pressures at the discharge side of the pump 82.

The unit 84 is provided at its ends with enlarged chambers 85 and 86 closed by threaded plugs 87 and 88, respectively. Intermediate the chambers 85 and 86 is a passage 89 of reduced diameter forming at its opposite ends valve seats 90 and 91. A reservoir passage 92 extends transversely from the unit 84 into the interior of the reservoir 83 and communicates with the reduced passage 89 intermediate the valve seats 90 and 91. Valve elements 93 and 94 are provided adjacent the valve seats 90 and 91, each of these valves being provided with a central port 95, as best illustrated in Figure 7. The valves 93 and 94 are of non-circular shape and are illustrated in Figure 9 as being hexagonal so as to provide for flow of fluid through the reduced passage either from end to end or from one end to and through the transverse reservoir passage 92. The ends of the pin 96 are provided with reduced extending portions 97 which are herein illustrated as conical and being of a diameter at their base substantially equal to the diameter of the port 95 formed in the valves. Intermediate the projecting end portions 97, the pin 96 is of somewhat larger diameter than the ports 95 formed in the valves so that when said valves are retained against the enlarged intermediate portion of the pin 96 as by spring pressure, the ports 95 are closed.

Balancing spring means are provided and take the form of compression springs 98 engaging the ported valves 93 and 94 at one end and seated at the other end against the plugs 87 and 88, these plugs being provided with centering projections 99 to retain the springs in centered relationship.

Means are provided for connecting chambers 85 and 86 to opposite sides of the pump 82 and these means take the form of passages 101 and 102 extending transversely from the chambers 85 and 86 respectively, and communicating with the internal and external gear members of the pump 82.

The operation of this embodiment of the invention is similar to that of the embodiment illustrated in Figure 1. When the pump is idle the springs 98 retain the pin 96 in centered po-

sition and the valves 93 and 94 are both retained away from their corresponding valve seats 90 and 91. At this time a by-pass is open between opposite sides of the pump comprising the passage 101, chamber 85, reduced passage 89, chamber 86 and passage 102. By virtue of this arrangement a by-pass flow of fluid is permitted when the pump is idle. Therefore, the mechanism to which the pump is connected may be operated manually.

If now the pump is started in either direction pressure will build up at the pressure side thereof which communicates with the chamber 85 or 86 and this pressure will force the valve 93 or 94 onto its corresponding valve seat, thus closing the by-pass passage. However, closure of either valve 93 or 94 results in further opening of the other valve, thereby maintaining open the passage connecting the suction side of the pump with the interior of the reservoir to permit flow of fluid to or from the reservoir to compensate for unequal flow of fluid to and from the hydraulic motor.

If an excessive pressure is built up in either the chamber 85 or 86 as a result, for example, of interference with the normal operation of a device actuated by the hydraulic motor, the by-pass connection between opposite sides of the motor is again opened. This is accomplished by virtue of the pressure acting against one end of the pin 96 through the port 95 in the chamber subjected to the high pressure. When this pressure exerts a force sufficient to overcome compression of the spring opposing movement of the pin 96 away from the valve subjected to the excessive pressure, the pin 96 moves bodily away from said valve and thereby opens the port 95 in the valve. Accordingly, by selecting the strength of the balancing springs 98, the maximum pressure which the pump 82 will deliver may be determined.

It is emphasized that the present construction represents a substantial improvement over my prior construction, particularly as to compactness, simplicity of mounting, efficiency of operation and the economy with which the construction may be produced.

The drawings and the foregoing specification constitute a description of the improved hydraulic power unit in such full, clear, concise and exact terms as to enable any person skilled in the art to practice the invention, the scope of which is indicated by the appended claims.

What I claim as my invention is:

1. In a hydraulic power unit, a pump housing block having a circular pump recess in its up-

per surface, an internally toothed pump gear having a cylindrical exterior rotatable in said recess, an externally toothed pump gear in said recess and meshed with said internally toothed gear, said pump gears extending upwardly above the upper surface of said block, a fluid supply reservoir having a bottom wall supported directly upon the upper surface of said block, said bottom wall having a circular opening therein in registration with said circular recess and forming an upward extension of said recess, the upper surface of the bottom wall of said reservoir being coplanar with the upper surface of said pump gears, a valve body in said reservoir having a flat under-surface resting upon the bottom wall of said reservoir surrounding the opening therein, the under-surface of said valve body constituting a closure for the upper end of the pump recess, fluid passages in said valve body terminating in ports at the under-surface of said body communicating with said pump recess, valves in said body controlling the flow of fluid to and from said reservoir, and fastening means assembling said pump housing block, reservoir, and valve body comprising fastening elements extending through said valve body and the bottom wall of said reservoir laterally outwardly from said pump recess into said pump housing block.

2. Structure as defined in claim 1 which comprises a removable top cover for said reservoir, and means for securing said cover in place on said reservoir comprising a rod carried by said valve body and extending upwardly therefrom through said reservoir, and means on said rod engaging said cover.
